JOSEPH LETCHWORTH, OF BUFFALO, NEW YORK.

Letters Patent No. 96,016, dated October 19, 1869.

IMPROVED BREAST-STRAP ATTACHMENT FOR HARNESS.

The Schedule referred to in these Letters Patent and making part of the same.

To all whom it may concern:

Be it known that I, JOSIAH LETCHWORTH, of the city of Buffalo, in the county of Erie, and State of New York, have invented a certain new and useful Improvement in Breast-Strap Attachments; and I do hereby declare that the following is a full and exact description thereof, reference being had to the accompanying drawings, in which—

Figure I is a perspective view of my improved attachment.

Figure II is a longitudinal section of the same, attached to the breast-strap.

Figure III is a cross-section.

Like letters of reference indicate like parts in each of the figures.

My improvement relates to that class of inventions known as breast-strap slides, which consists of a metal casting, attached to the breast-strap, to protect the leather from the abrading action of the neck-yoke ring, and to retain, or partially retain the said ring in place at the centre of the strap.

In the manufacture of light castings, the great object to attain is cheapness of construction, as the saleability of such articles as breast-strap slides depends mainly on the price, many devices, otherwise good, having failed of success, on account of the cost required to manufacture them.

The object of my invention is to produce a breast-strap attachment, that can be afforded at a less price than those in ordinary use, and also be more convenient, and better adapted for the purpose required.

My invention consists of a breast-strap attachment, as a new article of manufacture, cast of malleable iron, with the outer surface, contiguous to the strap, transversely corrugated, and each end provided with two

fingers, cast at right angles to the plate, which are afterward bent down, so as to overlap the edges of the strap on the outside and by clamping the strap against the corrugated surface, securely hold the attachment in place, without the use of rivets, or other expensive fastening.

In the drawings—

A represents my improved attachment, curved in the usual manner, with a flange, *a*, at the edges, which serve to stiffen the plate, and assist in retaining the strap *d* in place.

i i are the transverse corrugations on the outer side, against which the strap comes in contact.

b b are the fingers, cast so as to project at right angles from the main plate, as shown in Figs. I and III, where one of the fingers is represented as bent down, and the other in the position in which it is cast.

The plate being applied to the strap, as shown, the fingers, overlapping the edges of the strap on the outside, will serve to clamp the latter with sufficient force against the corrugations *i*, to prevent the attachment from being slid or displaced on the strap, by the surging or swaying of the neck-yoke.

If required, the fingers may be cast with spurs *c*, which, by indenting the leather, will render the attachment still more unyielding.

What I claim as my invention, is—

The breast-strap attachment A, as a new article of manufacture, cast of malleable iron, with fingers *c c* and transverse corrugation *i*, substantially as and for the purpose hereinbefore set forth.

JOSIAH LETCHWORTH.
